UNITED STATES PATENT OFFICE

PETER GRAHAM MACGREGOR, OF PEQUANNOCK, NEW JERSEY, ASSIGNOR TO PYRENE MANUFACTURING COMPANY, OF NEWARK, NEW JERSEY, A CORPORATION OF DELAWARE

FIRE EXTINGUISHER

Application filed July 11, 1928. Serial No. 291,871.

My present invention relates to fire extinguishers and it has for its object to provide certain improvements in the valve mechanism and also in the means employed in assembling the parts whereby the chambers may be securely locked together, the securing devices also serving as one of the parts for supporting the device as a whole.

The form of fire extinguisher with which
10 my improvements are intended to be used
comprises fluid and gas pressure chambers
and the valve mechanism embodying my in-
vention comprises means for simultaneously
controlling the passage of air or gas from
15 the pressure chamber to the fluid chamber
and the exit of the fluid expelled from the
last mentioned chamber. In accomplishing
these objects my invention further compre-
hends separate valve heads seating in valve
20 chambers and operated simultaneously in op-
posite directions by actuating devices ar-
ranged exterior of the valve chambers.

To these and other ends the invention also consists in certain further improvements and combination of elements all as will be fully described and particularly pointed out in the appended claims.

In the drawings:

Figure 1 is a front elevation of a fire extinguisher showing one embodiment of my invention.

Figure 2 is a view of the extinguisher as seen from the right in Figure 1, the major portion of the liquid chamber being shown in section.

Figure 3 is a plan view of the fire extinguisher shown in Figure 1, the valve mechanism being shown in section.

Figure 5 is a central vertical sectional view taken on the line 5^x—5^x of Figure 3.

Similar reference numerals in the several

45 figures, indicate similar parts.
The present invention may be embodied in

fire extinguishers adapted for various uses, and my invention is designed particularly to provide a structure of this character and also one which is adapted for use with airplanes and similar structures in which space is lim-

ited. The construction is such that it may be detachably connected to a suitable part of an airplane by brackets (10) and (11), hereinafter more particularly described.

The extinguisher includes an outer shell (12) forming a fluid or liquid chamber and an inner or pressure chamber (13), the walls of the two chambers being spaced an appreciable distance from each other to accommodate an appreciable and adequate supply of a suitable fire extinguishing liquid between them. The chambers (12) and (13) are preferably seamless in construction, and are closed at their respective upper ends by a common head (15). 55 60 65

The head (15) is preferably in the form of a casting provided with concentric flanges (16) and (17), provided with grooves as shown in Figures 4 and 5, receiving the upper ends of the chamber walls (12) and (13). A union of the inner and outer chambers with the head is made by soldering the upper ends thereof in their respective grooves. The head (15) also carries a centrally disposed internally screw-threaded boss (18) to which is connected a tie-rod (19), the lower end of which is provided with a shoulder (20) and projects through the bottom of the inner container (13) where it is soldered or otherwise so connected with the bottom of the inner container as to form an air tight joint. The lower end of the tie-rod (19) projects through the bottom of the container (13) and is provided with screw threads and is adapted to receive an internally screw-threaded plug 70 75 80 85

(21) which is soldered or otherwise connected to the bottom of the outer container (12) to form a liquid-tight joint. The plug (21) forms a support on which the bottom of the extinguisher may rest and in cases where the device is to be retained in a fixed position the plug (21) is provided with a depending screw-threaded portion (22) which will project through one arm of the supporting bracket (10) to which it is secured by a nut 90 as shown in Figures 1, 2 and 5. 95

An opening (24) (Figure 4) is formed in the head (15) to receive a suitable air check valve (25), the stem of which is provided with a removable cap (26). Upon removal 100

of the latter, a suitable air pump, not shown, or other source of air pressure may be connected to the valve stem (25) for the purpose of charging the pressure chamber (13). The pressure within the chamber (13) is indicated by a suitable pressure gauge (28), the stem of such gauge being inserted and secured in the opening (29) formed in the head (15).

The transfer of the pressure from the chamber (13) to the liquid chamber (12), as well as the escape of the fire extinguishing liquid from the chamber (12), when subjected to such pressure, is controlled by a suitable valve mechanism, the details of which are best shown in Figure 3. This mechanism is carried by the head (15) and includes an air or pressure valve head (31) and a liquid or fluid valve head (32), both valves being arranged for reciprocatory movement within a housing (33) preferably formed integral with the head (15) and arranged to provide separate valve chambers. The housing (33) is drilled from opposite ends to provide an air passage (34) and a liquid passage (35) which communicate, respectively, with the pressure chamber (13) and liquid chamber (12) through suitable ports (36) and (37) which extend upwardly from the bottom of the head (15), as viewed in Figure 5. The air valve chamber is provided at its inner end with a tapered seat surrounding the end of the passage (34) and with which the correspondingly shaped end of the valve head engages. The inner end of this valve head is reduced so as to provide a passage between the seat and an air duct (39) leading to the liquid chamber (12). The liquid valve differs from the air valve in that its end is flat and engages an annular bead (40) which serves as a seat therefor at the outlet end of the liquid passage (35). The valve head (32) at its inner end, is reduced to provide a liquid passage (41) which communicates with a discharge pipe (42) through which the fire extinguishing liquid is directed in case of a conflagration. Both of the valve heads (31) and (32) are reduced at their outer ends and project outwardly through suitable stuffing boxes, including gland nuts (43) and (44), respectively, which serve to limit them in their respective opening movements upon being engaged by the stop shoulders (45) and (46) formed on the heads. From the described arrangement of the valve heads (31) and (32), it will be understood that when they are in their closed positions as shown in Figure 3, communication between the pressure and fluid chambers is closed and that communication is closed between the discharge pipe (42) and the pick-up pipe (47) which communicates with the liquid passage (35) through the port (37). It will also be understood that when the valve heads (31) and (32) are retracted, or moved outwardly in opposite directions, communication be-

tween the air chamber and liquid chamber is established through the ports (36) and (39), and that communication between the pick-up pipe (47) and the discharge pipe (42) is established through the port (37), passage (35) and liquid valve chamber (41).

It is desirable in a device of this character to operate the valve heads practically simultaneously; to provide for the opening of the fluid valve to a greater extent than the air valve; to assure their engaging their respective seats with sufficient pressure when closed, and to allow a certain flexibility in the operating mechanism thereby obviating the necessity of too great a refinement in the construction or adjustment of the parts in order that the seating of one valve head slightly in advance of the other may not interfere with the proper and accurate seating of the latter.

The actuating mechanism controlling the valve heads comprises a single oscillatory shaft and arms cooperating therewith which are attached to the valve heads and cooperate with fixed stops on the casing which act as fulcrums when the valve heads begin to engage their seats.

To these ends the extremities of the valve heads (31) and (32) are suitably connected to arms (48) and (49), respectively, which extend laterally in the same direction and preferably project over the top of the head (15). At their free ends these arms are provided with adjustable stop-screws (50) and (51), the former of which is adapted to engage a projection or lug (52) carried by the head (15) and the other similarly cooperating with an abutment or lug (53) preferably cast integral with said head.

The prime mover comprises a shaft (56) which extends parallel to the valve heads and is provided with right and left hand screw threaded portions (54) and (55), which engage similarly threaded openings in the two arms (48) and (49). The latter rest in sliding engagement upon the head (15) and support the shaft, one end of which carries a sleeve (58) which is held between the shoulder formed at the outer end of the screw threads (55) and the hub of a hand wheel (60) rigidly fixed to the shaft. The sleeve is supported for longitudinal movement in a bracket (59) so that in the event a longitudinal movement is imparted to the shaft by the arresting of the movement of either valve head in advance of the other a compensatory action may be had sufficient to allow the other valve head to be seated without cramping the action of any of the movable parts. For instance, when the hand wheel is rotated counter clockwise, in Figures 1 and 3, the right and left hand screws separate the arms (48) and (49) and if the valve head (31) reaches the limit of its movement and it is desired to open the fluid valve a still greater distance, the con-

tinued partial rotation of the shaft will cause it to be moved bodily by the action of the threads (54) in the arm (48).

As the valves (31) and (32) are moved to their respective open positions, fluid pressure is transmitted from the pressure chamber (13) to the liquid chamber (12) through the port (36), air valve chamber (38) and airduct (39), the fluid pressure being utilized within the liquid chamber (12) to force the contents thereof upwardly from its lower end through the pick-up pipe (47), and out through the discharge pipe (42) by way of the port (37), liquid passage (35) and liquid valve chamber (41). By the arrangement and construction of the various parts entering into the valve actuating mechanism, it will be apparent that a given movement of the hand wheel (60) in a counterclockwise direction, as viewed in Figure 1, will cause only a relatively slight movement of the valve (31), whereas considerable movement is imparted to the valve (32), the relative movement of the valve heads (31) and (32) with respect to each other being desirable for the reason that only a slight opening of the valve (31) is necessary to permit unrestricted flow of compressed air therethrough, whereas a greater opening of the valve (32) is desirable in order to permit unrestricted release of the fire extinguishing liquid.

If desired, the hand wheel (60) may be provided with an actuating lever (61) provided at its outer end with a plurality of openings (62), which serve to enable a rope or chain to be easily attached to the lever so that the extinguisher may be operated from a remote point, as for example, when the device is used in connection with an airplane.

After operating the apparatus, the liquid chamber (12) may be refilled with a fire extinguishing liquid by removing the usual type of filler cap (64) and introducing the liquid until it rises to a height where it can be seen through the sight glass (65) suitably mounted in the wall of the liquid chamber (12). The valve heads (31) and (32) may be returned to their respective closed positions either before or after the liquid chamber (12) is filled with liquid, but such valves must be closed before attempting to recharge the pressure chamber (13), as will be readily understood. In moving the valves to their respective closed positions, the valve (31) is first seated whereupon the shaft (56) is caused to move longitudinally until the hub portion of the hand wheel (60) engages the bearing (59) as shown in Figure 3. After such engagement has been established, continued rotation of the shaft causes the valve head (32) to continue to move until such time as it engages its seat. As the valve heads (31) and (32) engage

their respective seats, the screws (50) and (51) engage their respective abutments so that the valve actuating arms (48) and (49) are relieved of any undue strain or stresses when forcing the valves into firm engagement with their respective seats, such undue strains or stresses being obviated by reason of the fact that the thrusts at opposite ends of the valve actuating arms (48) and (49), respectively, are equalized at the time the valve heads (31) and (32) engage their respective seats, as will be readily understood.

Having thus described the invention, what is claimed is:

1. In a fire extinguisher, gas and fluid chambers having a connecting passage, the fluid chamber being provided with a fluid outlet, separate valve heads controlling said passages, said heads being offset relatively to each other and disposed for parallel axial movement in opposite directions, and an actuator disposed in a plane at one side of the valve heads and arranged to simultaneously move said heads in opposite directions to alternately open and close said passages.

2. In a fire extinguisher, gas and fluid chambers having a connecting passage, the fluid chamber being provided with a fluid outlet, separate valve chambers disposed in said passage and arranged with their axes offset, a valve head in each valve chamber, and means exterior of the latter for simultaneously moving said heads in a direction away from each other to open said passage.

3. In a fire extinguisher, gas and fluid chambers, valve chambers having seats and provided one with passages for connecting said gas and fluid chambers and the other having an outlet for the fluid chamber, a valve head in each valve chamber, and means offset from the axes of said chambers for moving the valve heads axially in opposite directions simultaneously.

4. In a valve control mechanism, the combination with two valve chambers, valve heads therein extending in opposite directions, and arms extending laterally therefrom, of a rotatable operating shaft and right and left hand screw thread connections between said shaft and arms.

5. In a valve control mechanism, the combination with two valve chambers, valve heads therein extending in opposite directions, arms extending laterally from the valve heads, of an operating shaft having right and left hand screw thread connections with said arms and stops cooperating with the arms for limiting their movement relatively toward each other.

6. In a valve control mechanism, the combination with two valve chambers, valve heads therein extending in opposite directions, of an operating shaft at one side of and parallel to said heads mounted for rotary movement and limited longitudinal move-

ment, arms attached to the latter and having right and left hand screw thread connections with said shaft and adjustable stops cooperating with the arms and limiting their relative movement.

7. In a valve control mechanism, the combination with two valve chambers, valve heads therein extending in opposite directions, parallel arms extending laterally from the valve heads and connected thereto at one end and stops cooperating with the opposite ends of the arms for limiting their relative movement, of a rotatable shaft having right and left hand screw thread connections with intermediate points of said arms.

8. In a fire extinguisher, a fluid chamber for a fire extinguishing fluid, a pressure chamber for a compressed gas, a pressure valve controlling the passage of pressure from said pressure chamber to said fluid chamber, a fluid valve controlling the passage of fluid from said fluid chamber, said valves comprising heads movable in opposite directions, a revoluble actuating shaft having different portions provided with oppositely pitched screw threads, and actuating arms connecting said valve heads to the screw threaded portions of said shaft for transmitting movement to said valves in opposite directions upon rotation of said shaft.

9. In a fire extinguisher, a fluid chamber for a fire extinguishing fluid, a pressure chamber for a compressed gas, a pressure valve controlling the passage of pressure from said pressure chamber to said fluid chamber, a fluid valve controlling the passage of fluid from said fluid chamber, said valves comprising heads movable in opposite directions, a revoluble actuating shaft having different portions provided with oppositely pitched screw threads, actuating arms connecting said valve heads to the screw threaded portions of said shaft for transmitting movement to said valves in opposite directions upon rotation of said shaft, said valve actuating arms being provided with fulcrum extensions, and stop means adapted to operate with said fulcrum extensions upon seating of said valve heads to equalize the thrusts imparted thereto by said shaft.

10. In a fire extinguisher, a fluid chamber for a fire extinguishing fluid, a pressure chamber for a compressed gas, a pressure valve controlling the passage of pressure from said pressure chamber to said fluid chamber, a fluid valve controlling the passage of fluid from said fluid chamber, said valves comprising heads movable in opposite directions, a revoluble actuating shaft having different portions provided with oppositely pitched screw threads, actuating arms connecting said valve heads to the screw threaded portions of said shaft for transmitting movement to said valves in opposite directions upon rotation of said shaft, said

valve actuating arms being provided with fulcrum extensions, stop means adapted to co-operate with said fulcrum extensions upon seating of said valve heads to equalize the thrusts imparted thereto by said shaft, and adjustable means for varying the time at which a cooperative relation is established between said stop means and said fulcrum extensions with respect to the closing movement of said valve heads.

11. In a fire extinguisher, a fluid chamber for a fire extinguishing fluid, a pressure chamber for a compressed gas, a pressure valve controlling the passage of pressure from said pressure chamber to said fluid chamber, a fluid valve controlling the passage of fluid from said fluid chamber, said valves comprising heads movable in opposite directions, a revoluble actuating shaft having different portions provided with oppositely pitched screw threads, actuating arms connecting said valve heads to the screw threaded portions of said shaft for transmitting movement to said valves in opposite directions upon rotation of said shaft, a sleeve carried by said shaft, and a bearing in which said sleeve is movably mounted.

12. In a fire extinguisher, a fluid chamber for a fire extinguishing fluid, a pressure chamber for a compressed gas, a pressure valve controlling the passage of pressure from said pressure chamber to said fluid chamber, a fluid valve controlling the passage of fluid from said fluid chamber, said valves comprising heads movable in opposite directions, a revoluble actuating shaft having different portions provided with oppositely pitched screw threads, actuating arms connecting said valve heads to the screw threaded portions of said shaft for transmitting movement to said valves in opposite directions upon rotation of said shaft, a shoulder provided upon said shaft, an operating member carried by said shaft, a sleeve carried by said shaft and confined thereon intermediate said shoulder and said operating member, and a bearing in which said sleeve is slidably mounted.

13. In a fire extinguisher comprising a head, a fluid chamber having one end secured to and closed by said head, a pressure chamber having one end secured to and closed by said head, the other end being spaced from the corresponding end of said fluid chamber and a tie-rod common to said chambers, said tie-rod being connected at one of its ends to said head and at its other end to said chambers.

14. In a fire extinguisher comprising a head, a fluid chamber having one end secured to and closed by said head, a pressure chamber having one end secured to and closed by said head, the other end being spaced from the corresponding end of said fluid chamber and a tie-rod common to said

chambers, said tie-rod being connected at one of its ends to said head and at its other end to said chambers, an extension carried by said other end of said tie-rod, and a supporting bracket secured to said extension.

15. In a fire extinguisher comprising a head, a fluid chamber having one end secured to and closed by said head, a pressure chamber having one end secured to and closed by said head, the other end being spaced from the corresponding end of said fluid chamber and a tie-rod common to said chambers, said tie-rod being connected at one of its ends to said head and at its other end to said chambers, an extension carried by said other end of said tie-rod, a supporting bracket secured to said extension, and a clamp ring embracing one of said chambers, said bracket and clamp ring serving collectively as a support.

20 In testimony whereof, I have affixed my signature to this specification.

PETER GRAHAM MacGREGOR.
